CALENDAR

Karl Wüstefeld, Brunswick, Germany

Application July 15, 1932, Serial No. 622,736, and
in Germany September 30, 1931

10 Claims. (CL 46—197)

My invention relates to improvements in calendars, and more particularly in calendars of the type in which time-controlled means are provided for successively removing the leaves of a block at the beginning of the day. The object of the improvements is to provide a calendar of this type which is simple in construction and reliable in operation, and with this object in view my invention consists in providing each leaf at both sides with slots which are open to the same side and which are used for suspending the leaves on a pair of projecting pins so that the leaves may be removed by being shifted by time-controlled mechanism in lateral direction. Preferably the slots of the superposed leaves are open alternately to opposite sides so that they are alternately shifted in opposite directions, and a lower leaf is held in position on the pins when the uppermost leaf is shifted away from the pins.

For the purpose of explaining the invention several examples embodying the same have been shown in the accompanying drawings in which the same reference characters have been used in all the views to indicate corresponding parts. In said drawings,

Fig. 1 is an elevation showing the calendar and the time-controlled mechanism for removing the leaves.

Fig. 2 is a sectional elevation taken on the line 30 2—2 of Fig. 1.

Fig. 3 is a sectional plan view taken on the line 3—3 of Fig. 2.

Fig. 4 is a sectional plan view similar to the one illustrated in Fig. 3 and showing the parts in a different position.

Fig. 5 is an elevation showing a modification in which a two-armed lever the ends of which are fork-shaped is employed.

Figs. 6 and 7 are fragmentary elevations showing the block of the leaves, Fig. 6 showing a leaf the slots of which are open to the left, and Fig. 7 showing the following leaf the slots of which are open to the left.

Fig. 8 is an elevation showing a modification in which mechanical means are provided for controlling the operation of the leaf-shifting mechanism.

Fig. 9 is a sectional elevation taken on the line 45 9—9 of Fig. 8.

Fig. 10 is a fragmentary front and side elevation showing a detail.

Fig. 11 is a sectional plan view taken on the line 50 11—11 of Fig. 9, and

Fig. 12 is a similar sectional plan view showing 55 the parts in a different position.

In the construction shown in Figs. 1 to 7 the calendar is mounted on a front plate 1, and it comprises a block of leaves 3 supported on the front plate 1 by means of pins 4 and 5 fixed to the said plate. At the rear side of the plate 1 a clock is mounted the dial 2 of which is visible from the front side of the plate 1. The pins 4 and 5 are located one beside the other in a horizontal plane and they provide supports for the leaves of the block 3. As is shown in Figs. 6 and 7 the leaves are provided at their top sides with a cutout portion 8 thus producing flaps 7, and the said flaps are provided with horizontal slots 6 and 9. In Fig. 6 the uppermost leaf which bears the date September 8 has slots open to the right, and in the next leaf, which is shown in Fig. 7, and which bears the date September 9 the slots 6 and 9 are open to the left. The lengths of the slots 6 and 9 are such that holes 4¹ and 5¹ are provided which extend through the body of the block, 60 and which have the pins 4 and 5 passed therethrough when the block of leaves is in position, as is best shown in Fig. 3. It appears therefore that the leaf shown in Fig. 6 and bearing the date September 8 may be removed from the pins 4 and 5 by being shifted to the left, and in the meantime the next leaf, which bears the date September 9, is held in position by the ends of the slots 6 and 9, which are open to the left, engaging the pins 4 and 5. The next leaf shown in Fig. 7 and bearing the date September 9 is removed by being shifted to the right, and when it is thus shifted the next leaf bearing the date September 10 is held in position, because its slots open to the right and thus permit shifting to the left only.

As appears from Figs. 2 and 3 the pins 4 and 5 have a length such that they project forwardly of the block of leaves 3. On the said projecting ends of the pins 4 and 5 a pressure plate 10 is mounted by means of sleeves 11, the said pressure plate being guided on the said pins so as to be shiftable towards the block 3. To the pressure plate 10 two screws 12 are fixed which bear with their inner ends on the front side of the top part of the block, and on the front side of the said pressure plate a bracket 38 is provided which is formed with an eye providing a bearing for a shaft 13. To the bottom end of the said shaft an arm 14 is secured which carries a block 15 of rubber at its free end. The length of the arm 14 is such that it projects inwardly beyond the pressure plate 10 when it is perpendicular thereto and into engagement with the uppermost leaf of the block 3. To the top end of the shaft 13 a lever 16 is secured which has a pin 17 fixed to its outer 65 70 75 80 85 90 95 100 105 110

end. The pressure plate is held with the ends of the screws 12 in engagement with the block 3 by a weighted body 39 and a cord 38 trained on a roller 37 and attached to said pressure plate.

5 In a slot 18 a two-armed lever 19 is rockingly mounted the arms of which are formed with longitudinal slots 20 and 21. The slot 20 engages the pin 17 of the lever 16, and the slot 21 engages a pin 24 fixed to a rotary disk 23 adapted to be 10 rotated by a spring motor 22. The said disk 23 is formed with four bores 25, 26, 27, 27¹ which are arranged thereon on a circle and in diametrically opposite pairs, the bores 27, 27¹ and 25, 26 of the pairs being located close to each other. The said 15 bores are adapted to be engaged by a locking pin 30, which is acted upon by a spring 28 tending to push the same into engagement with the holes, and the electromagnet 29 adapted to retract the same from the holes. The coil of the electromagnet 29 is connected by leads 32 and 33 with a source 31 of electric energy and a spring-pressed switch 34, 35 which is normally open, and which is adapted to be automatically closed by the small hand 40 of the clock engaging the spring arm 35 of the switch. When the said hand 40 engages the spring arm 35 it retracts the same away from the contact 34, and when the spring arm is released it is thrown towards and into engagement with the contact 34, from which it is 20 immediately retracted by its spring action. Thus the circuit of the electromagnet 29 is temporarily closed and immediately opened again. Thereby a current impulse flows through the electromagnet 29, by which the locking pin 30 is retracted from the hole 25, 26, 27 or 27¹ in opposition to the spring 28, so that the spring motor 22 imparts movement to the disk 23. The electromagnet 29 immediately releases the pin 30, which is therefore pushed by the spring 28 towards the 25 disk 23, on which it slides until it engages the next bore 25 to 27.

40 Fig. 5 shows a modification of the calendar in a representation similar to Figs. 3 and 4. This modification differs from the modification shown in Figs. 3 and 4 in the substitution of the lever 19 provided with two longitudinal slots 20, 21 and serving for the transmission of the movement from the rotary disk 23 to the lever 16 by a two-armed lever 191 the ends of which have the form of two-pronged forks 201, 211.

45 Shortly before twelve o'clock at night the parts provided for operating the arm 14 are in the positions shown in Fig. 3, the disk 23 being locked in position by the pin 30 engaging in the bore 25. By the current impulse caused by the hand 40 the disk 23 is released from the pin 30, and it is turned anticlockwise and in the direction of the arrow *x* by the spring motor 22. Therefore the 50 arm 14 is rocked to the left and in the direction of the arrow *a* shown in Fig. 3 through the intermediary of the levers 19 and 16. Thus the uppermost leaf of the block 3, for example the leaf shown in Fig. 6 and carrying the date September 8, is shifted to the left and away from the pins 4 and 5, the slots 9 and 6 being open to the right, while the next leaf, for example the leaf shown in Fig. 7, is held in position on the pins by the flaps 7, so that it cannot be carried along by friction. The disk 23 is rotated until the pin 30 is thrown 55 into engagement, by the spring 28, with the bore 27¹ and locks the disk 23 in position.

60 When the hour hand again passes the 12 of the clock, that is at noon, the switch 34, 35 is again momentarily closed, and the pin 30 is retracted from the bore 27¹ and immediately

thereafter released again. Now the disk 23 is slightly turned, because the pin 30 immediately engages in the adjacent bore 27, and the parts are in the positions shown in Fig. 4. When the hand 40 again passes the 12, that is at midnight of the next day, the disk 23 is turned until the pin 30 engages the bore 26. Thereby the arm 16 is rocked to the right and the next leaf, that is the leaf shown in Fig. 7, of the block 3 is shifted to the right and removed from the block. When the switch is again operated, that is at noon of the next day, the pin 30 engages the bore 25 of the disk 23 without removing a leaf from the block.

65 In the modification illustrated in Figs. 8 to 12, I have shown mechanical means in lieu of the electromagnetically controlled operating mechanism for the disk 23. As shown in the said figures in the front wall 80 of a casing 41 a clock 42 is mounted (Figs. 8 and 9). The hour hand 43 of the said clock is fixed to a sleeve 44 mounted concentrically of the arbor 45 of the minute hand 46, the said sleeve and arbor being connected by a gearing 47, 48, 47¹ and 48¹, as is known in the art. To the sleeve 44 a cam 49 is secured which takes the form of a bail extending longitudinally of the axis of the sleeve. On a screw 50 projecting inwardly from the front wall 80 of the casing 41 a lever 51 is rockingly mounted, which bears on the sleeve 44 and which is 70 adapted to be lifted by and dropped from the bail 49. On a bolt 58 projecting inwardly from the front wall 80 of the casing 41 a lever 54 is mounted, which is connected with the lever 51 by means of a link 53 jointed to the lever 51 and 52 and engaging the lever 54 substantially at the middle of the arm 54¹. From the end of the arm 54¹ a small weighted body 55 is suspended. To the other arm 54² of the lever 54 a link 57 is pivoted by means of a bolt 56. 75 The bottom end of the said link 57 takes the form of a hook 59 which cooperates with a leaf spring 62 secured to a screw 61 fixed to the front wall 80. At its free end the said leaf spring carries a locking nose 64 and it is formed with a slot 63 which is engaged by the hook-shaped end 59 of the link 57. Below the leaf spring 62 a driving disk 70 is mounted which is parallel to the front wall 80. The said driving disk 70 is formed at its circumference with two pairs of notches 65, 66 and 67, 68, and it is adapted to be rotated by means of a spring motor 69, the said disk being adapted to be locked in position by the nose 64 engaging in any one of the notches 65, 66, 67 or 68. The pairs of notches 65, 66 and 67, 68 80 are diametrically opposite to each other. As is best shown in Fig. 10, the notches 65, 66, 67, and 68 are produced by cuts made in the disk at its circumference and bending the tongues thus produced outwardly. The tongues 95 are 85 used for rocking the hook 59.

85 To a pin 71 secured to the disk 70 a rod 72 is pivoted which is connected with the downwardly directed arm of a lever 73 rockingly mounted on a pivot bolt 74 projecting rearwardly from the front wall 80. The top end of the said lever 73 is connected by a horizontal rod 75 with an arm 76 passed through a horizontal slot 87 made in the front wall 80 and secured to a vertical shaft 77. The said shaft is 90 rockingly mounted in a bearing 79 carried by a pressure plate 78 disposed in front of the wall 80. To the bottom end of the said shaft a gripper 82 is secured the free end of which carries a rubber finger 81. The said gripper has a 95

length such that its rubber finger 81 projects beyond the pressure plate 78 when it is perpendicular to the said plate. Its object is to shift the calendar leaves from the block. The shape 5 of the said leaves is the same as has been described with reference to Figs. 1 to 7.

Near each of its ends the pressure plate 78 carries a guide roller 83 which is formed with a circumferential groove bearing on one of the 10 pins 84 supporting the block 85. Above each guide roller a screw 86 is fixed to the plate 78, which screws bear with their ends on the top part of the block of leaves 85. From the middle of the plate 78 a guide rod 89 extends rearwardly and through a bore 88 made in the front wall 80, and the said guide rod is guided internally of the wall 80 on a circumferentially grooved roller 91 mounted on the bracket 90. At the bottom of the groove the said roller 91 is formed 15 with a narrow groove on which a thread 92 is trained one end of which is fixed to the pressure plate 78, while the opposite end has a weighted body 93 suspended therefrom by means of which the pressure plate 78 is held, with its screws 86, in engagement with the block 85. Below the block 20 85 there is a chute 94 adapted to collect the leaves removed from the block and to conduct the same into the casing 41.

The operation of the apparatus is as follows: 25 In the position of the parts of the clock shown in Figs. 8 and 9 the hour hand is shortly before twelve o'clock at noon. When the hour hand 43 approaches the 12 on the dial the bail 49 secured to the sleeve 44 of the hour hand lifts the lever 51 and the link 53. Thereby the lever 54 is rocked in clockwise direction and the link 57 is moved downwardly while sliding in the slot 63 of the leaf spring 52. If now the hour hand 43 exactly indicates the 12 on the dial, the bail 49 arrives in the 30 position in which the lever 51 is adapted rapidly to drop therefrom and into initial position, the downward movement of the lever 51 being assisted by the weighted body 55. Thus the hook 59 is rapidly pulled upwardly, so that the nose 64 of the spring 62 is retracted from the notch 66. Therefore the disk 70 is adapted to be advanced in the direction of the arrow *y* shown in Fig. 8 by the spring motor 69. This free movement continues until the tongue 95 of the notch 66 35 engages the lower end 60 (Fig. 9) of hook 57 and shifts the same out of engagement with the leaf spring 62, whereupon the nose 64 engages the notch 65. During this short rotary movement of the disk 70 the rods 72, 73, 75, 76, 82 perform a 40 small movement which is not sufficient to cause a leaf to be removed from the block 85.

At twelve o'clock at night the mechanism is operated in a similar way. But by reason of the 45 large distance between the notches 65 and 67 the disk 70 is rotated through a larger angle until the said disk is again arrested by the nose 64 engaging in the notch 67. By this large partial rotary movement of the disk 70 a leaf is shifted laterally and away from the block 85 through the intermediary of the gearing 72, 73, 75, 76, 82.

The leaves of the blocks which are supported 50 on the pins 4, 5 or 84, and which are formed with laterally open slots may have advertising matter or other information printed thereon.

I claim:

1. A calendar comprising a support for a block of leaves, a friction member engaging the exposed surface of the outermost leaf of the block, and time-controlled mechanism for moving said 55 member transversely of the face of the block to remove successive leaves therefrom. 80

2. A calendar, comprising a support, a pair of parallel pins secured to said support, a block of leaves supported on said pins, each leaf having a cut-out portion between said pins and slots extending from said pins in the same direction and respectively to said cut-out portion and to the margin of the leaf, a friction member mounted for moving in frictional engagement with the uppermost leaf of said block in a direction substantially parallel to said slots to move said leaf off from said pins, and time-controlled mechanism for operating said friction member. 85

3. A calendar, comprising a support, a pair of parallel pins secured to said support, a block of leaves supported on said pins, each leaf having a cut-out portion between said pins and slots extending from said pins respectively to said cut-out portion and the margin of the leaf the slots in alternate leaves extending respectively in opposite directions from said pins, a friction member mounted for moving in frictional engagement with the uppermost leaf of said block in a direction opposite to the direction of the slots and substantially parallel to said slots, and time-controlled mechanism for moving said friction member alternately in opposite directions to remove successive leaves from said pins. 90

4. A calendar comprising means for supporting a block of leaves, a friction member engaging the face of the outermost leaf of the block, means for moving said friction member in a direction transverse to the face of said leaf to remove the leaf from the block, means for locking said automatically operating member alternately after performing a small movement and a large movement, means for throwing said locking means out of and into locking engagement, and a clock controlling the operation of said throwing means. 105

5. A calendar, comprising a support, a pair of parallel pins secured to said support, a block of leaves supported on said pins, each leaf having a cut-out portion between said pins and slots extending from said pins respectively to said cut-out portion and to the margin of the leaf the slots in the successive leaves extending alternately in opposite directions from said pins, a friction member mounted for moving in frictional engagement with the uppermost leaf of said block in a direction opposite to that of the slots and substantially parallel to said slots, an operating member adapted to move said friction member alternately in opposite directions to remove successive leaves from said pins, locking means adapted to lock said operating member alternately after performing a small operating movement and a large operating movement, and a clock adapted to throw said locking means out of and into locking engagement. 110

6. A calendar, comprising a support, a pair of parallel pins secured to said support, a block of leaves supported on said pins, each leaf having a cut-out portion between said pins respectively to said cut-out portion and to the margin of the leaf the slots in the successive leaves extending alternately in opposite directions from said pins, a friction member mounted for moving in frictional engagement with the uppermost leaf of said block in a direction opposite to that of the slots and substantially parallel to said slots, a rotary operating disk adapted to move said friction member alternately in opposite directions to remove successive leaves from said pins, said disk 120 125 130 135 140 145 150

being formed with shoulders alternately disposed close to each other and at a large distance, a locking member cooperating with said shoulders, an electromagnet adapted to throw said locking member out of and into locking engagement with said shoulders, and a clock adapted temporarily to energize said electromagnet.

7. A calendar, comprising a support, a pair of parallel pins secured to said support, a block of leaves supported on said pins, each leaf having a cut-out portion between said pins and slots extending from said pins respectively to said cut-out portion and to the margin of the leaf the slots in the successive leaves extending alternately in opposite directions from said pins, a friction member mounted for moving in frictional engagement with the uppermost leaf of said block in a direction opposite to that of the slots and substantially parallel to said slots for removing said leaf from said pins, a rotary operating disk, a crank pin on the disk, a crank arm adapted to operate said friction member, a rockingly mounted two-armed slotted lever connecting said crank pin and crank arm for transforming the rotary movement of said disk into rocking movement of said crank arm, said disk being formed with shoulders alternately disposed close to each other and at a large distance, an electromagnet having an armature adapted for locking engagement with said shoulders, a spring acting on said armature and tending to throw the same into locking engagement with said shoulder, means to send current impulses to said electromagnet, and a clock controlling said sending means.

8. A calendar, comprising a support, a pair of parallel pins secured to said support, a block of leaves supported on said pins, each leaf having a cut-out portion between said pins and slots extending from said pins respectively to said cut-out

portion and to the margin of the leaf, the slots in the successive leaves extending alternately in opposite directions from said pins, a friction member mounted for moving in frictional engagement with the uppermost leaf of said block in a direction opposite to that of the slots and substantially parallel to said slots to remove said leaf from said pins, a rotary operating disk, a crank pin on said disk, a crank arm adapted to operate said friction member, a rockingly mounted two-armed slotted lever connecting said crank pin and crank arm for transforming the rotary movement of said disk into rocking movement of said crank arm, said disk being formed with shoulders, an electromagnet and its armature adapted for locking engagement with said shoulders, a spring acting on said armature and tending to throw the same into locking engagement with said shoulders, means to send current impulses to said electromagnet, and a clock controlling said sending means.

9. A calendar comprising means for supporting a block of leaves, a friction member engaging the exposed face of the outermost leaf and movable across the face of the block to remove the outermost leaf therefrom, an operating member connected with said friction member, a clock having a cam on an arbor connected with the hour hand, and mechanism acted upon by said cam for controlling the movement of said operating member.

10. A block of superposed calendar leaves each formed at its top with a cut-out portion to provide corner flaps and slots in said flaps extending in each leaf respectively from said cut-out portion into one flap and from the margin of the leaf into the other flap, said slots being disposed in the successive leaves in opposite senses.
